TEMPERATURE CONTROL APPARATUS FOR REFRIGERATORS

Harold W. Schaefer, Rosemont, Pa., assignor to Philco Corporation, Philadelphia, Pa., a corporation of Pennsylvania

Application March 22, 1952, Serial No. 277,947

3 Claims. (Cl. 257—9)

The invention hereinafter disclosed and claimed is concerned with refrigeration control, relating especially to refrigerators of the type in which a single evaporator, or other cooling means, provides refrigeration within each of a pair of adjacent compartments.

In considering the invention it is to be borne in mind that it has proven desirable to provide within a refrigerated cabinet not only a freezer compartment, but also a compartment maintained at a temperature above the freezing point of water, and in which may be preserved fresh fruits, vegetables, or other foodstuffs which should not be subjected to sub-freezing temperatures. A relatively simple and inexpensive way of constructing such a refrigerator comprises dividing the space defined by the inner liner of the cabinet into upper and lower compartments by means of a generally horizontal partition or baffle which limits, but does not eliminate, circulation of air between said upper and lower compartments. The partition is so shaped and disposed within the cabinet as normally to provide for limited circulation of cooling air between the two compartments, and this may be accomplished most readily by spacing the front and rear edges of the partition from the adjacent walls of the cabinet. Commonly the refrigeration system is responsive to the temperature of the evaporator which cools (and the walls of which may define) the freezer compartment, and this invention has to do with refrigerators of the foregoing type in which at least the major portion of the cooling within the higher temperature compartment is accomplished by circulating air from the latter compartment around said baffle or partition and in heat exchange relation with the evaporator of the freezer compartment.

While constructions of the type described are well known and are advantageous, they have been found, in practice, to be subject to a difficulty, particularly in that a reduction in the ambient temperature may result in over-cooling of the fresh food compartment and even in freezing of foods therein. This has proven to be the case even though an adjustable, flow-restricting damper be provided to limit the passage of air about the partition.

Accordingly, and with the foregoing in mind, it is the primary object of the present invention to overcome the above-mentioned difficulty by making it possible to restrict or to eliminate the circulation of air about the baffle which separates the two compartments and, particularly, to provide for conjoint restriction of circulation and addition of heat to the cabinet. More specifically the invention has as an object effecting advantageous control of the heating means through the agency of means which restricts circulation.

In an important aspect of the invention it is contemplated that the heat shall be applied in such a way as to operate to limit circulation of air between the two compartments of a refrigerator, and that application of the heat shall be under the control of a damper which further serves to restrict circulation of air around the baffle.

Broadly, application of heat in such manner as to serve as means limiting circulation of air about the baffle of a refrigerator is fully described and claimed in the co-pending application of Lloyd A. Staebler, bearing Serial No. 277,774, filed March 21, 1952, and assigned to the assignee of the present invention. As indicated above it is with improved apparatus for controlling the application of heat that the instant invention is particularly concerned.

In accordance with the said co-pending disclosure,

2

means is provided which is effective to apply heat in the region of that edge or portion of the baffle about which downflow of cooled air normally takes place. It has been found that application of a relatively small quantity of heat in this region creates an upward current of warmed air which is in opposition to the normal downward flow of air effective to cool the lower compartment. When heat is applied in this way the quantity of heat required to prevent undue reduction of the temperature within the lower compartment is considerably less than the quantity which would be required if the heat were to be applied at a location remote from the baffle. There is created what might be referred to as a "heat block" impeding or substantially preventing the normal circulatory flow of air around the baffle and, consequently, serving to reduce the effectiveness of the upper evaporator in cooling the lower compartment. The Staebler invention is particularly concerned with utilization of this heat block as the sole means for controlling the flow of air around the baffle.

Further, and as indicated above, efforts have been made to limit the cooling within the lower compartment by the use of a pivoted damper which may be moved, with relation to the baffle, to a position such that it impedes the normal exchange of air around the baffle, and thereby correspondingly reduces the circulatory flow of air which is the primary source of cooling for the lower compartment. As indicated above, this expedient has not alone proven to be satisfactory and, with respect to the Staebler invention, it is to be noted that the Staebler apparatus necessitates the use of a switch or some suitable control circuit for energizing the heater when the ambient temperature is relatively low.

In particular accordance with my invention, a heater is utilized—preferably being mounted near the baffle in general accordance with the teaching of the aforesaid Staebler disclosure—and the baffle damper is made to serve two purposes in that it not only contributes to the desired limitation of air flow, but also because it operates as a means for controlling energization of the heater. As will become more clear as the description proceeds, the present invention involves recognition of the fact that the heater should preferably be energized conjointly with closing of the damper.

The manner in which the foregoing objects and advantages may best be achieved will be understood from a consideration of the following detailed description, taken together with the accompanying drawings, in which:

Figure 1 is a vertical, sectional illustration of a refrigerator of the type to which the invention is particularly applicable;

Figure 2 is a somewhat diagrammatic view of the upper portion of the inner liner of a refrigerator, showing an advantageous way in which the heater may be applied to the outer surfaces of the liner, and illustrating the heater supply circuit and control switch;

Figure 3 is a fragmentary, front elevational view, on an enlarged scale, illustrating the upper portion of a refrigerator of the type shown in Figure 1;

Figures 4 and 5 are fragmentary, sectional views illustrative of the manner in which air circulates under different conditions of operation; and,

Figure 6 is a sectional view showing latch means which may be employed to hold the damper in open position.

Now making more detailed reference to the drawings, and particularly to Figures 1, 2 and 3 thereof, it will be seen that the invention is therein illustrated as embodied in a domestic refrigerator comprising an outer shell 10 and an inner shell or liner member 11, spaced inwardly of and insulated from the outer shell 10 by means of any suitable insulation, shown at 12. A pair of doors 13 and 14 are adapted to seat against the forward face of the cabinet and provide independent access to different sections of the cabinet. It will be understood that the refrigerator also includes a compressor-condenser unit of any desired type, but illustration of this portion of the apparatus is not necessary herein since the present invention is not concerned therewith.

As clearly appears in the drawing, the space within the inner liner 11 is sub-divided into an upper relatively low temperature storage compartment defined by an evaporator 15 and a lower, food storage compartment

16, by means of a tray-like partition or baffle designated by the reference character 17. As is clear from a comparison of Figures 1 and 3, both the evaporator 15 and the baffle 17 substantially span the width of the space defined by the inner liner, the baffle 17 being so shaped and disposed within the cabinet as to provide an upflow zone or space 18 at the forward edge thereof and a downflow zone 19 along the rear edge thereof.

The center cross-rail 20 against which the adjacent edges of the doors seal, provides support, through the agency of a hinge member 21, for an adjustable damper 22 having therein a depression or pocket 23 (see particularly Figures 4 and 5). This damper also spans the width of the cabinet and, as aforesaid, serves not only as an aid in limiting circulation of air around the baffle 17, but also as a means for controlling the application of heat.

Turning now to the heating means, and making reference to Figures 2, 4 and 5, the heater 24, which preferably comprises several loops of relatively high resistance wire secured in convoluted arrangement across the outside of the back surface of inner liner 11, is disposed at the general level of the rear edge of the partition 17, that is, in the region of the downflow gap or aperture 19. It will be observed that the heater substantially spans the width of the cabinet, thereby insuring that the applied heat will be effective along the entire back edge of baffle 17.

The heater, which is illustrated diagrammatically in Figures 4 and 5, is secured to the back surface of the inner liner in any convenient manner, a strip of adherent tape, 25 (Figure 2) being used for this purpose. A pair of terminals shown at 26 are adapted for connection to any suitable source of power, and the heater is placed across the line through conductors 28 and 29 and through the agency of a plunger type switch 27, which is mounted in the cross-rail 20.

As appears in Figures 4 and 5 the plunger 30 which actuates the switch extends outwardly of the cross-rail 20 and toward the aforesaid pocket 23 formed in the confronting portion of damper 22. The damper is movable between an open position shown in Figure 4, in which position the plunger 30 is depressed by contact with the pocket 23 and the heater is de-energized, and a closed position in which the damper bridges the gap between the cross-rail structure and the baffle and bears against the forward edge of the latter. In this closed position of the damper the plunger 30 is of course extended and the contacts of the switch are closed, thereby effecting energization of the heater 24. Referring to Figure 6 it will be seen that the damper may conveniently be provided with an aperture 31 cooperable with a manually operable latch member 32 effective to hold the damper in its open position. As will be pointed out hereinafter the latch is released and the damper is lowered during seasons, and under conditions, when over-cooling of the lower compartment 16 might be expected.

When the damper 22 occupies the open position shown in Figure 4, that is, when there is no substantial possibility of over-cooling the lower compartment 16, the operation of the refrigerator is characteristic of known apparatus of the kind in which circulation of air around the baffle is utilized to provide cooling of the compartment below said baffle. The normal circulatory flow of air is represented by the arrows applied to Figure 4 and this normal phase of operation will be understood without further description.

When it is desired to limit cooling of the lower compartment, a condition which most commonly obtains during the colder months of the year when the ambient temperature may drop rather sharply, the latch 32 is released and the damper is moved to the closed position shown in Figure 5. Movement of the damper to this latter position serves not only to limit the circulation of air upwardly across the forward edge of the baffle 17, but also, as aforesaid, energizes the heater element 24. The heat generated by the element 24 not only adds directly to the heat load normally resulting from leakage through the cabinet insulation, but also warms the adjacent portion of inner liner 11 and results in turbulence at the vicinity of the rear edge of the baffle 17 and, ultimately, in creation of a zone or column of warm air tending to flow upwardly around the rear edge of the baffle, as is indicated by the arrows applied to Figure 5. This turbulence and upward flow of warmed air which constitutes the "heat block" referred to hereinabove, to-

gether with the direct addition to the cabinet heat load, serves very effectively to prevent excessive cooling of the lower compartment 16. It has been found that an input of approximately twelve watts is sufficient to accomplish the purposes of the invention, and it will be appreciated that application of wattage as low as this is not sufficient to interfere appreciably with the proper operation of the evaporator 15 or with its ability to maintain frozen foods at the proper, predetermined temperature.

Under this latter condition of operation, and due to the conjoint action of the damper and the application of heat, the normal circulatory flow of air between the two compartments is virtually terminated, although a relatively slow circulatory flow of air continues to take place within said lower compartment, as is represented by arrows shown below the baffle in Figure 5.

Due to the fact that in a refrigerator of the type to which the invention is applicable there is normally provided freedom for air flow across both the forward and the rear edges of the baffle, or through suitably spaced apertures provided in the baffle, it will be appreciated that closing of the damper alone is not sufficient to eliminate interchange of air between the two compartments, since air cooled within the upper compartment is still free to flow downwardly into the lower compartment through the gap or aperture not provided with a damper, displacing an equal amount of air which flows upwardly through the same gap or aperture. When, on the other hand, a small amount of heat is applied conjointly with closing of the damper 22 it is readily possible to prevent excessive cooling within the lower compartment.

During the day, the temperature of the kitchen or other room in which the refrigerator is located tends to rise considerably, as compared with the over-night temperature, and it might at first appear that application of heat together with closing of the damper would result in insufficient cooling of the lower compartment or in objectionable interference with the recovery characteristics of the refrigerator. This however has not proven to be the case, as will be appreciated when it is recognized that during colder seasons of the year, when closing of the damper and use of the heater is most advantageous, the relative humidity of the ambient atmosphere is low. Under conditions of low relative humidity the evaporator and other cooled surfaces of the refrigerator are fully effective in transferring sensible heat, rather than having a considerable portion of the capacity utilized in effecting transfer of latent heat—with resultant condensation of moisture—as occurs during warmer seasons when the relative humidity is higher.

In practice it has been found that maintenance of satisfactory temperatures within the lower compartment during the winter season requires no more attention from the user of the refrigerator than is necessitated by closing of the damper with resultant automatic energization of the heating means.

From the foregoing description it will be understood that my invention provides an improved refrigerator in which undue reduction in the temperature of the fresh food compartment is prevented by the simple expedient of causing the damper to serve the dual purposes described above, and this result is accomplished without in any way interfering with the maintenance of the low temperatures desired within the freezer compartment.

The invention, in its broader aspect, contemplates location of the heater in positions other than the position shown and described herein; for example, the heater might be so situated, at a level further down the inner liner within the food storage compartment, that the air heated thereby rises toward the normal downflow aperture of the baffle assembly and therefore creates a rising current of air which is in counter-flow relation with respect to the circulation which obtains under normal operating conditions. It will be recognized however that the foregoing, and such other changes as may come within the scope of the appended claims, are within the purview of the invention.

I claim:

1. In refrigeration apparatus, a cabinet, a baffle or partition disposed within said cabinet and separating the space therein into upper and lower compartments, the upper of said compartments having cooling means in heat exchange relation therewith, and said baffle having a first edge portion spaced from a wall portion of the cabinet

and another edge portion spaced from another wall portion of the cabinet, whereby to provide for limited circulation of cooling air between said two compartments, and means preventing over-cooling of said lower compartment, comprising: heating means associated with the said other wall portion of said cabinet in substantial adjacency to the said other edge portion of said baffle; movable damper means cooperable with said first edge portion of said baffle to restrict the stated circulation of air; and control means including said movable damper means and effective to initiate operation of said heating means.

2. Refrigeration apparatus in accordance with claim 1, and further characterized in that said heating means comprises an electrical resistance heater extending along the said other wall portion of the cabinet, and being of a length substantially equal to the length of the said other edge portion of the baffle.

3. In refrigeration apparatus, a metallic inner liner member defining a storage compartment, a baffle mounted generally horizontally within said inner liner member and having portions disposed in spaced adjacency with re-

spect to interior surface portions of one wall of the inner liner member to provide a gap through which air may flow, the construction and arrangement being such that air normally circulates downwardly through the gap and thence returns upwardly past other portions of said baffle, and means for impeding such normal circulation of air, comprising: an adjustable damper providing for variation in the flow of air through said gap; an electrical resistance heater mounted upon an exterior surface portion of the said adjacent wall of the inner liner member; and switching means for controlling said heater, said switching means being operable in response to adjustment of said damper.
